William P. Lear, North Hollywood, Calif., assignor, by mesne assignments, to Lear, Incorporated, Piqua, Ohio, a corporation of Illinois

Application November 22, 1943, Serial No. 111,759

Term of patent 14 years

(Cl. D26—5)

To all whom it may concern:

Be it known that I, William P. Lear, a citizen of the United States of America, residing at North Hollywood, in the county of Los Angeles, in the State of California, have invented a new, original, and ornamental Design for a Rotary Actuator Unit for Movable Parts of an Aircraft, of which the following is a specification, reference being had to the accompanying drawings, forming a part thereof.

In the drawings:

Fig. 1 is a perspective view of a rotary actuator unit for movable parts of an aircraft embodying the present design.

Fig. 2 is a right end elevational view of the unit illustrated in Fig. 1.

Fig. 3 is a plan view of the unit illustrated in Fig. 1.

Fig. 4 is a side elevational view of the unit illustrated in Fig. 1.

Fig. 5 is a front elevational view of the unit illustrated in Fig. 1.

I claim:

The ornamental design for a rotary actuator unit for movable parts of an aircraft, substantially as shown.

WILLIAM P. LEAR.
